UNITED STATES PATENT OFFICE.

MICHAEL B. KENDIS, OF SEDALIA, MISSOURI.

JEWELRY-DISPLAY TRAY AND HOLDER.

1,278,354.

Specification of Letters Patent. Patented Sept. 10, 1918.

Application filed January 9, 1918. Serial No. 211,014.

To all whom it may concern:

Be it known that I, MICHAEL B. KENDIS, a citizen of the United States, residing at Sedalia, in the county of Pettis and State of Missouri, have invented certain new and useful Improvements in Jewelry-Display Trays and Holders, of which the following is a specification.

This invention relates to devices for displaying rings and other articles of jewelry or the like, and it is the object of the invention to provide a novel holder for readily receiving and effectively holding a ring or other article for display in a show case, counter, store window or the like.

Another object of the invention is the provision of a clean and sanitary mounting for such holders, which is washable and fade-proof.

A further object is to provide a novel tray for utilizing the holders and displaying the articles.

A still further object is the provision of such a device, which will be simple and inexpensive in construction and manufacture, and practical and serviceable in use.

With the foregoing and other objects in view, which will be apparent as the nature of the invention is better understood, the invention resides in the arrangement and construction of parts hereinafter described and claimed, it being understood that changes within the scope of what is claimed can be made without departing from the spirit of the invention.

The invention is illustrated in the accompanying drawings, wherein—

Figure 1 is a perspective view of the tray with the holders.

Fig. 2 is a vertical section thereof.

Fig. 3 is a fragmentary perspective view of one corner of the tray showing one of the supporting clips.

Fig. 4 is a plan view of one of the holders.

Fig. 5 is a section on the line 5—5 of Fig. 4.

Fig. 6 is a perspective view of a display card having one of the holders thereon.

The holders, as shown in Figs. 4 and 5, each comprise a pair of semi-circular blocks 7, of wood or other suitable material, forming a circular clamp, although the same can be of any desired contour. The arcuate sides of the jaws or blocks 7 are provided with grooves 8, thereby providing the clamp or holder with a circumferential annular

groove, in which is seated an annular spring or band 9, constructed of coiled wire as illustrated, and having a contractive tension, whereby said spring in embracing the jaws will contract the clamp and move the confronting flat sides of the jaws together when there is no article between them. The corners of the jaws, between the confronting sides and outer faces thereof, are provided with chamfered arcuate notches 10, for the ready insertion of the ring or other article into the holder. Thus, when the article is introduced into the recess formed by said notches and pushed into the holder, the notches serve to center the article in the holder and also cause the jaws to separate, so that the article passes between the confronting sides thereof, to be firmly held in place. The spring 9 yields as the jaws separate and clamp the article between them, and the jaws can separate different distances for articles of various widths or sizes. The jaws move together as soon as the article is withdrawn.

A number of the holders, as shown in Figs. 1 and 2, are embodied in the tray, which includes a sub-bottom or base 12 of wood or the like, and the tray proper is formed from sheet metal or its equivalent, and comprises the bottom 13 having the upturned marginal rim 14 in turn provided with the downturned apron 15 of greater width or height than the rim 14 so as to project below the plane of the bottom 13. The apron 15 forms the sides of the tray and is inclined to facilitate stacking. Thus, the lower edges of a number of trays stacked one on the other, can fit over the upper edges of the aprons 14, to prevent the trays slipping, and enable them to be conveniently placed in a safe at night or otherwise handled. The lower edge portion of the apron 14 is bent back or reflexed inwardly to not only stiffen the same, but to also support the sub-bottom 12 which is fitted upwardly within the apron below the bottom 13. Supporting clips 17 are inserted over the edge portion 16 after the sub-bottom is introduced, and are preferably located within the corners of the apron. These clips are secured to the lower surface of the sub-bottom by means of screws 18 or the like, and therefore support the sub-bottom. By removing the screws 18 and clips 17, the parts of the tray can be readily taken apart for repairs or cleaning.

The bottom 13 of the tray is provided with a suitable number and arrangement of upstruck bosses or raised portions 19 having central openings 20 forming surrounding lips 21 overhanging and overlapping the holders which are seated on the sub-bottom underneath and within the bosses, thus holding the parts in place. The holders in being within the bosses are limited thereby in the separation of the jaws. The openings 20 expose the holders for the insertion of the articles, and said articles in projecting upwardly from the holders through said openings will be displayed and shown off to advantage, it being noted that the bosses serve to make the articles stand out individually, making them more noticeable and therefore also enabling theft to be more quickly detected and thwarted. The sheet metal covering or top of the tray is enameled in any suitable color (different color schemes thus being possible for different articles to help show them off) and this makes the tray clean and sanitary, for the reason that it can be washed off with a damp cloth, and the enamel will not fade. The trays are thus of permanent construction, and will have a long life.

It is preferable to cement or otherwise fasten one jaw or part of each holder on the sub-bottom 12, to hold the same in a given position and thus neatly arrange the articles, while the other jaws are movable bodily from the fixed ones. The jaws or parts of the holders rest on the surface of the sub-bottom or plate 12, and the loose jaws are slid able freely in all directions on the surface of the plate parallel therewith. Although the tray is shown as being rectangular in form, it may be of different shapes. This tray may be of different designs and colors, and the enameling improves its effectiveness.

In Fig. 6 there is shown one of the holders applied to a display card or plate 30 of metal or the like, and having its surface enameled to render it sanitary and washable. The holder is located within the area of said surface, like each of the holders of the tray, so that the surface surrounding the holder can be kept clean. One part or jaw of the holder is cemented or otherwise fastened to the card, while the other is freely movable to and fro bodily to conform to various articles. The surface of the card has suitable legends or other data 31 of permanent character thereon protected by the enamel, and price numerals 32 or the like can be pasted, printed, painted or otherwise placed thereon, so as to be readily removed or washed off to make changes.

Having thus described the invention, what is claimed is:

1. A display device embodying a supporting plate, a pair of jaws seated on said plate,

one slideable freely on the plate in all directions parallel to the plate relative to the other jaw which is fixedly mounted on said plate, and spring means for moving said jaws together and permitting free movement of the movable jaw on said plate. 70

2. A display device embodying a supporting plate, a pair of similar jaws seated thereon, one fastened to the plate and the other free to slide thereon in all directions 75 parallel to the plate, and an annular contractive spring embracing the jaws to draw them together and permit free movement of the movable jaw on said plate.

3. A display device embodying a supporting plate, a pair of semi-circular jaws seated on said plate and having their flat sides confronting one another to fit together, one of said jaws being secured to said plate and the other being slideable freely on the plate in 80 various directions, said jaws having grooves in their arcuate sides, and an annular contractive spring seated in said grooves and embracing the jaws to draw them together with their flat sides in contact, said jaws 90 having chamfered arcuate notches in those corners between said confronting sides and their faces to receive an article and cause the jaws to separate when the article is forced between them in said notches. 95

4. A display tray embodying a plate having spaced upstruck raised portions with openings therein, and holders supported from below said plate and located within said portions to be limited in movement 100 thereby.

5. A display tray embodying a bottom provided with openings, a sub-bottom, and individual article holders supported by said sub-bottom below said openings, the tray 105 bottom having means for limiting the movement of said individual holders under said openings.

6. A display tray embodying a bottom provided with raised bosses having openings 110 therein, a sub-bottom, and article holders supported by the sub-bottom under and within said bosses to be limited in movement thereby.

7. A display tray embodying a bottom formed of sheet material and having a marginal downturned apron, said bottom having openings for articles, a sub-bottom within the apron below said tray bottom to support said articles, and means for removably 120 supporting said sub-bottom from said apron.

8. A display tray embodying a bottom formed of sheet material and having a marginal upturned rim provided with a downturned apron extending below the plane of said bottom, said bottom having openings for articles, and a sub-bottom within said apron below said tray bottom for supporting said articles, said sub-bottom being above the lowermost portion of said apron 125 130

to permit stacking of a number of the trays with their aprons overlapping.

9. A display tray embodying a bottom having openings therein for articles, said bottom having a marginal upturned rim provided with a downturned apron, said apron having a lower inwardly extending portion, a sub-bottom within the apron below said tray bottom, and fasteners carried by said sub-bottom and seating on said portion to support the sub-bottom so that it

supports said articles, said fasteners being removable from said portion to permit the sub-bottom to be removed.

10. A display tray embodying a bottom 15 having raised bosses with openings therein, and a marginal downturned apron, a sub-bottom within and supported by said apron, and article holders seated on the sub-bottom under and within said bosses to be limited 20 in movement thereby on said sub-bottom.

MICHAEL B. KENDIS.
